MASSAGING MACHINE

Application filed October 21, 1929. Serial No. 401,181.

The invention is related to massaging machines in which a strap is engaged with the portion of the body to be massaged and is rapidly reciprocated by the machine. It is the principal object of the present invention to provide a unique construction useable with this conventional reciprocatory strap for the purpose of operating a plurality of rollers which carry out a kneading action upon the flesh and muscles, instead of merely vibrating the skin without any material massaging action, as in the present-day machines.

A further object is to provide means whereby the roller-carrying device may be connected with the reciprocatory strap if desired, to reciprocate therewith, but under normal circumstances may lie stationarily against the body with the strap moving over the rollers to rotate the latter.

With the foregoing and minor objects in view, the invention resides in the novel subject matter hereinafter described and claimed, description being accomplished by reference to the accompanying drawings.

Fig. 1 is an elevation partly broken away, showing the roller-carrying device and the reciprocatory strap slidably engaged with each other.

Fig. 2 is a longitudinal sectional view on line 2—2 of Fig. 1, showing the ends of the roller carrier connected with the reciprocatory strap, the latter being slack between the two points of connection.

Fig. 3 is a transverse sectional view on line 3—3 of Fig. 1.

Fig. 4 is a transverse sectional view on line 4—4 of Fig. 2.

Fig. 5 is a fragmentary elevation showing a different form of construction.

Fig. 6 is an edge view partly broken away and in section, of the construction illustrated in Fig. 5.

Fig. 7 is an elevation partly broken away and in section showing a still further form of construction.

Figs. 8 and 9 are transverse sectional views on lines 8—8 and 9—9 respectively of Fig. 7.

Fig. 10 is an elevation partly broken away and in section illustrating a still further form of construction.

Fig. 11 is an edge view of the structure shown in Fig. 10.

Fig. 12 is a transverse sectional view on line 12—12 of Fig. 10.

Fig. 13 is an end elevation of a roller to be mounted eccentrically rather than concentrically.

Fig. 14 is a side elevation illustrating a longitudinally convex form of roller, this form and the cylindrical form shown in the other views, being merely two of many shapes which may be employed.

In the drawings above briefly described, S denotes the conventional strap of a massaging machine, adapted to be rapidly reciprocated by said machine, while engaged with one portion or another of the body. For use with this conventional strap, I provide an elongated carrier C provided with a plurality of flesh-engaging rollers R, and provision is made whereby the strap S and the carrier C may be directly connected with each other for movement in unison, and whereby these parts may be relatively disconnected so that the strap will slide with respect to the carrier, while engaging the rollers R. A number of different constructions are shown for the carrier C and that illustrated in Figs. 1 to 4 will first be described. Before so doing, however, attention may be invited to the facts that the rollers R for any form of carrier may be of the cylindrical shape shown in most views, of the longitudinally convex form shown in Fig. 14 or of any other desired formation, that said rollers may be mounted concentrically as in most views or eccentrically as in Fig. 13, that these rollers may be formed entirely of resilient material such as rubber or may be only rubber-covered, and that the shafts upon which the rollers are mounted, may either be fixed with the rollers rotatable upon them, or may rotate bodily with said rollers.

In Figs. 1 to 4, the carrier C is shown as embodying two parallel longitudinal side straps 15 of webbing, leather or other desired flexible material, the ends of these straps being connected by transverse pairs of end straps. One end strap of each pair is denoted at 16 and the other at 17, these straps

being secured against opposite sides of the straps 15 by stitching or other desired means 18. This construction forms a guide at each end of the carrier C, through which the strap S passes. Additional guide straps 19 are 5 stitched at their ends to the straps 15 for disposition at the side of the strap S opposite that at which the rollers R are disposed.

Two additional longitudinal straps 20 lie 10 against the straps 15 and are preferably of less width, the two sets of straps 15 and 20 being secured to each other by longitudinally spaced pairs of stitching lines 21 or other desired means. The strap portions between the 15 lines 21 of each pair, provide pockets 22 in which the ends of the roller shafts 23 are received as will be clear from Figs. 1 and 3. When this construction is followed, the shafts 23 are preferably non-rotatable and the rollers R are turnable upon them. Preferably, 20 the shafts 23 are shouldered at the ends of the rollers R and washers 24 are engaged with said shoulders, preventing the rollers from rubbing against the inner edges of the straps 15 and 20. In addition to securing these 25 straps together by the lines of stitching 21, short longitudinal lines of stitching 25 may be employed at the outer ends of the shaft-receiving pockets.

30 The device is placed against the body in such a position that the rollers R contact therewith, and when the strap S is reciprocated, it slides freely with respect to the carrier C but as it is in contact with said rollers, 35 causes driving of the latter to effectively knead or massage the flesh and muscles. If desired to drive the rollers by body contact instead of by contact with the strap S, the 40 ends of the carrier C may be connected with said strap S with slack in the latter between the two points of connection, thereby allowing reciprocation of the entire assemblage as a single unit. To permit attainment of this 45 end, I have shown openings 26 in the end straps 16-17, capable of alinement with similar openings 27 in the strap S, so that a tie 28 (Figs. 2 and 4) may be passed through the alined openings. The openings of the 50 strap S are longitudinally spaced apart a greater distance than those of the carrier C. Hence, when the two sets of openings are alined and the ties 28 passed through them and secured, the strap S will be slack between the two points of connection as illustrated in 55 Fig. 2, so that it will not then contact with the rollers R and cause unnecessary friction.

In Figs. 5 and 6, the side members 15^a of the carrier C are formed of light metallic links pivoted together, the pivots being preferably the ends of the roller shafts. Connected with these side members 15^a, are two U-shaped end links 16^a, each of which is suitably secured to a metallic guide loop 17^a through which the strap S passes. Other 60 guide straps 19^a, preferably of metal, may

be secured to certain of the links of the side members 15^a to engage the side of the strap S opposite the rollers R. Openings 26^a are shown in the loop 17^a for registration with similar openings 27^a in the strap S, allowing 70 connection of the carrier with the strap by use of a tie such as that above described. It may be stated at this point, that any desired means other than the openings and ties may be used for connecting the ends of the carrier with the strap-end, the present disclosure being for illustrative purposes only. 75

In Figs. 7, 8 and 9, the side members 15^b of the carrier C are formed of parallel strips of spring metal or other longitudinally flexible material. End loops 17^b similar to the loops 17^a may be secured to the ends of the strips B to slidably receive the strap S, and intermediate guides may be employed if desired. In this construction, the ends of the roller shafts are secured by rivets or the like 80 21^b, to the strips 15^b. In the end loop 17^b, and in the strap S, openings 26^b and 27^b have been shown to receive a tie such as 28 above 85 described.

In Figs. 10 to 12, the side members 15^c of the carrier C, are in the form of resilient wires having their ends secured at 18^c to transverse end loops 17^c which may be considered as substantially identical with the loops 17^b. At spaced points, the wires 15^c carry appropriate bearings 21^c for the ends of the roller shafts, and these shafts may either rotate within or be held by said bearings, as desired. 90

95 From the foregoing, taken in connection with the accompanying drawings, several ways of constructing the invention will be understood and it will be obvious that numerous other variations may be made within the scope of the invention as claimed. The carrier C with its rollers may either be attached to the strap S to reciprocate bodily therewith, or the strap may reciprocate with respect to the carrier, as may be most desirable, and in either instance, the rollers will produce effective massaging and kneading actions upon the surface flesh and also upon the deeply seated muscles, providing a more thorough massaging action than that obtained with the mere reciprocation of a strap or the like lying against the skin. Moreover, there is less danger of chafing the flesh and causing soreness. 105 110 115

If desired, instead of connecting the device with the strap S as seen in Fig. 2, its ends may be connected with two short straps corresponding to the end portions of said strap S in Fig. 2, for the intermediate portion of said strap S is slack and could well be omitted. 120 125

I claim:—

1. A device of the class described comprising a reciprocatory strap, a plurality of rollers disposed transversely at one side of and 130

being adapted to contact with said strap, and a longitudinally flexible carrier upon which said rollers are mounted for rotation, said carrier extending longitudinally of said strap and having guides through which said strap passes slidably, whereby reciprocation of the strap will drive the rollers.

2. A device of the class described comprising a reciprocatory strap, a plurality of rollers disposed transversely at one side of and adapted to contact with said strap, a longitudinally flexible carrier upon which said rollers are mounted for rotation, said carrier having guides through which said strap passes, and releasable means for connecting the ends of said carrier to said strap with slack in the latter between the points of connection, when desirable to drive the rollers by body contact instead of by contact with the strap.

In testimony whereof I have hereunto affixed my signature.

PAUL L. HEMP.
